UNITED STATES PATENT OFFICE.

PETER ENDRES, OF INDEPENDENCE, KANSAS.

DISAPPEARING FOOT SCRAPER.

Application filed February 19, 1925. Serial No. 10,374.

To all whom it may concern:

Be it known that I, PETER ENDRES, a citizen of the United States, residing at Independence, in the county of Montgomery and

6 State of Kansas, have invented certain new and useful Improvements in Disappearing Foot Scrapers; and I do declare the following to be a full, clear, and exact description of the invention, such as will enable others 10 skilled in the art to which it appertains to make and use the same.

My invention relates to improvements in devices for scraping mud from persons' shoes, and while the device is intended primarily for use in connection with the running boards of automobiles, it may also be employed in connection with the steps and porches of buildings.

The principal object of the invention is 20 to provide a device of the class described which will be extremely simple and inexpensive, yet will be highly efficient and desirable, may be quickly and easily attached, may be hidden from view when not in use, 25 may be quickly moved to an operative position when needed, and will be yieldably held in either operative or inoperative position.

Another important object of the invention 30 is to provide a foot scraper in which the foot scraping blade is disposed in a steeply inclined plane, so that said blade will be self-cleaning.

With the foregoing in view, the invention 35 resides in the novel subject matter herein-after described and claimed, the description being supplemented by the accompanying drawing.

Figure 1 is a vertical sectional view 40 showing the cleaner in a retracted inoperative position.

Figure 2 is a duplicate of Fig. 1 with the exception that it illustrates the cleaner extended for use.

45 Figure 3 is a vertical sectional view as indicated by line 3—3 of Fig. 1, and by the line 1—1, this view indicates the plane on which Figs. 1 and 2 are cut.

Fig. 4 is a bottom plan view.

50 Fig. 5 is a perspective view of the scraping plate and its carrying arms.

In the drawing above briefly described, the numeral 1 designates a horizontally elongated scraping blade which is disposed 55 in a steeply inclined plane, so that it will be self-cleaning. Welded, brazed or otherwise

secured to the ends of the blade 1, so as to form integral parts thereof, are two parallel supporting arms 2, said arms projecting horizontally at right angles from the lower edge portion of said blade and being adapted to contact slidably with the lower side of an automobile running board 3 or with any other appropriate support. Each of these arms is formed with an inner longitudinal slot 4 and with an outer longitudinal slot 5, the inner slots receiving attaching bolts 6 passing through the support 3, while comparatively long bolts 7 are passed through said support and through the outer slots 5. 60 The nuts 6^a of the bolts 6 contact with the lower sides of the arms 2, but the nuts 7^a of the bolts 7 are downwardly spaced from said arms, and washers 8 surround the bolts in contact with said lower sides of said arms. Coiled compression springs 9 also surround the bolts 7 between their nuts 7^a and the washers 8, said springs exerting an upward pressure to frictionally bind the washers 8 against the lower sides of the 65 arms 2, so as to yieldably hold the latter against the support 3, whether the device be forced to the retracted, obscured position of Fig. 1, or to the projected operative position disclosed in Fig. 2. The spring devices 70 also hold the device against rattling when it is used upon an automobile. 75

Preferably each arm 2 is of angle metal, with one flange disposed horizontally for contact with the support 3, while the other flange 10 projects downwardly and serves as locking means for the nuts 6^a and 7^a, so that the latter cannot work loose from the bolts and become lost.

Preferably, the blade 1 is provided with acute angular corners 11 which readily adapt themselves to scraping mud and the like from the edges of the shoe sole. The lower edge of this blade may well be provided with a downwardly projecting lug 12 to be 95 engaged by the hand or foot when withdrawing the device for use.

It will be seen from the foregoing that the invention is extremely simple and inexpensive, yet that it will be very desirable, may be quickly and easily attached to a running board or other support, will be substantially obscured when not in use, may be readily withdrawn when its use is desired, will be self-cleaning upon such use, will be yieldably 100 and anti-rattlingly held in either position, and will be generally advantageous.

As excellent results have been obtained from the details disclosed, they are preferably followed. However, within the scope of the invention as claimed, modifications 5 may of course be made.

I claim:

1. A foot scraper comprising a horizontally elongated scraping plate, a pair of parallel arms rigidly secured to said plate 10 and projecting horizontally therefrom to engage the lower side of a support, each arm having an inner longitudinal slot and an outer longitudinal slot, attaching fasteners passing through said slots and adapted also 15 for passage through a support, and a compression spring on at least one fastener of each arm for exerting a yieldable pressure to frictionally hold such arm in contact with the lower side of the support.
2. A structure as specified in claim 1; said fasteners being in the form of bolts having nuts on their lower ends, said arms being provided with downwardly projecting flanges which reinforce them and engage said 25 nuts to lock the latter against loosening.
3. A foot scraper comprising a horizon-

tally elongated blade disposed in a steeply inclined plane and having acute upper corners, a pair of parallel horizontal angle metal arms integrally secured to and projecting at right angles from said blade, one flange of each arm being horizontally disposed for contact with the lower side of a support while the other flange of such arm projects downwardly, said horizontal flanges each having an inner and an outer longitudinal slot, bolts passing through said slots and adapted also for passage through a support, nuts on the lower ends of said bolts engaging said vertical flanges and being thereby 30 locked against rotation, washers on certain of said bolts between their nuts and the horizontal flanges of said arms, and coiled springs on said certain bolts interposed between said washers and said nuts to force 35 said washers into binding frictional contact with the arms and to yieldably hold the latter against the support.

In testimony whereof I have hereunto affixed my signature.

PETER ENDRES.
